UNITED STATES PATENT OFFICE

EASTMAN A. WEAVER, OF BROOKLINE, MASSACHUSETTS, ASSIGNOR, BY MESNE ASSIGNMENTS, TO STATOR REFRIGERATION, INC., A CORPORATION OF DELAWARE

REFRIGERATING SYSTEM

Application filed August 23, 1924. Serial No. 733,899.

This invention relates to a refrigerating system of the type having an aspirator for impelling refrigerant vapor from a cooler to a condenser and employing a propellant fluid different from the refrigerant fluid, and more particularly to a system having a boiler for generating the propellant vapor, a vapor duct leading from the boiler to the aspirator, a liquid duct leading from the condenser to the boiler through which the propellant liquid returns to the boiler and in which a head of the propellant liquid balances the difference in pressure between the boiler and condenser. It has been recognized for many years that systems of this type offer unique possibilities, especially for small household installations, since they need no valves or moving mechanical parts and may be permanently sealed and will operate automatically. However, while offering great possibilities theoretically, no one has been able, so far as I am aware, to make a practical refrigerating system of this type.

Objects of the present invention are to overcome the practical difficulties which have heretofore prevented the development of a successful system of the aforesaid type and so to determine the many interrelated factors which are involved in a system of this kind that the apparatus is simple, compact, efficient and safe.

One important factor is involved in the differences in pressure and temperatures of the propellant fluid on the intake and outlet sides of the aspirator. If the temperature difference of the ratio of pressures is low the efficiency is low and if the pressure on the inlet side is excessive it is impractical to construct the apparatus to operate satisfactorily under high pressure. I have discovered that efficiency can be attained without employing high pressure apparatus by employing a propellant liquid having a boiling point higher than 100° C. (and preferably higher than 300° C.) at atmospheric pressure, and employing a refrigerant having a vapor pressure below 100 mm. (and preferably below 15 mm.) at 0° C.

Another factor which I have found to be very important is the shock loss in the aspira-

tor resulting from the impact of the molecules of propellant vapor against the molecules of refrigerant vapor; and I have discovered that this factor can be kept within practicable limits by employing a propellant vapor whose molecular weight is at least approximately four times the molecular weight of the refrigerant vapor.

A third factor which is most important, particularly in household installations, is the height of the head of propellant liquid required to balance the difference in pressure between the boiler and condenser. I have found that this head may be kept within practicable limits by employing a propellant liquid whose specific gravity is greater than two and preferably whose density is at least approximately fourteen times the density of the refrigerant liquid.

The two liquids should also be immiscible so that they may be readily separated and returned to the boiler and cooler respectively after their vapors commingle in the aspirator and are condensed.

The liquids which best fulfill all these conditions, so far as I am at present aware, are mercury and water. When using mercury as the propellant and water as the refrigerant good efficiency can be attained with a boiler pressure as low as one atmosphere. Other combinations of liquids (e. g. mercury and alcohol) meet a part or all of the above conditions and the invention is therefore not limited, except as recited in the appended claims, to the use of mercury and water.

In the accompanying illustration of a concrete form of apparatus for practising the invention—

Fig. 1 is a diagrammatic side view, partly in section; and

Figs. 2 and 3 are enlarged sections on lines 2—2 and 3—3 of Fig. 1.

Referring to the drawings the cooler may comprise a series of coils 1 mounted in transverse plates 2 to facilitate the transmission of heat from the region to be cooled, for example the interior of a refrigerator. The condenser is preferably mounted above the cooler so that the propellant and refrigerant fluids may be condensed therein and returned

respectively by gravity to the boiler and the cooler. In this instance the condenser comprises parallel tubes 4 and 5, preferably formed in one piece. A casing 7 surrounds the lower tube 4 for a portion of its length; and integral webs 8 extend between the tube 4 and casing 7 to facilitate the transmission of heat from the tube to atmosphere. The upper tube 5 is provided with a similar casing 9, which is integral with the casing 7 and extends substantially the entire length of the tube, and webs 10 integrally connect the tube 5 and casing 9 to afford a greater radiation.

The inlet end of the tube 4 is bent slightly upwardly as shown at 11 and a smaller tube 22 extends into the lowermost portion of end 11. The tube 22 extends outwardly and downwardly and terminates at its lower end in coils 13 which are located within the vaporizer 14. The vaporizer 14 may be of any suitable type and in this instance comprises a housing 15 having a burner 16, which is supplied with a gaseous fuel from the inlet 17, and a flue 18 surrounding ducts 12 and 22.

The arrangement of the condenser shown in the drawing permits the propellant liquid to be returned to the boiler hot, while the refrigerant liquid is returned to the cooler near room temperature. The mixed vapors entering the condenser first traverse the upward slanting hot portion 4 in which most of the propellant fluid is condensed and flows to the hot outlet 22, and the remaining vapors then traverse the cooler downward-sloping portion 5 in which most of the refrigerant vapor is condensed and flows to the cooler outlet 25. While the two condensing tubes are shown as air-cooled, one or both may be cooled in any suitable manner as by a water jacket: indeed, the condenser or condensers may be of any suitable construction.

The propellant liquid is vaporized in the vaporizer 14 and the vapor passes through the tube 12 and aspirator 18 consisting of a restricted orifice 19 and passage 19' tapering outwardly from the orifice so that the vapor as it passes therethrough expands approximately adiabatically with a large drop in pressure and great increase in velocity. The orifice and passage are preferably so designed that the pressure at the outlet of the passage is approximately equal to the pressure of the refrigerant vapor corresponding to the temperature at which it is designed to maintain the refrigerant liquid in the cooler. Where water is the refrigerant and a temperature of freezing is desired in the cooler, the pressure of the water vapor corresponding to water at 0° C. is approximately 4.6 mm. Between the outlet of the passage and the restriction 21, the refrigerant vapor is entrained in the stream of the propellant vapor. The molecules of propellant vapor give some of their energy to the molecules of refrigerant vapor, whereby the average trans-

lational speed of the refrigerant molecules is made substantially equal to that of the molecules of the propellant vapor. The velocity energy of the propellant vapor molecules is used up in the work of compressing the propellant and refrigerant vapors up to a back pressure corresponding to the vapor pressure of the refrigerant liquid in the condenser tube 5. In the case of water the back pressure will vary between 30 and 60 mm., depending on the room temperature and condenser efficiency. The condensed propellant flows through a portion of the tube 4, due to the inclination of the latter, into the feed pipe 22 which extends downwardly parallel to the tube 12 and terminates in coils 23, the lower end of pipe 22 being integrally connected to the inlet end of the coils 13. The propellant liquid in the pipe 22 serves as a static feed column for the vaporizer and the weight of the liquid in this pipe is sufficient to balance the pressure of the vapor in pipe 12 and coils 13.

The condensed water flows by gravity through the tube 5, due to the inclination of the latter, to a collecting chamber 24 into which extends an outlet pipe 25 above the bottom of the chamber. The water overflows into the pipe 25 which is connected at its opposite end to an intermediate coil of the cooling chamber 1. The pipe 25 is in this instance substantially U-shaped at its lower end in which there is a column 26 of relatively dense liquid, preferably mercury, which serves to maintain a lower pressure in the cooler 1 than in the condenser. The water flowing through the pipe 25 may have a vapor pressure of from 30 to 60 mm. and as it bubbles through the mercury column 26 it expands into the cooler in which the pressure is lower causing evaporation to take place.

The purpose of the collecting chamber is to cause the refrigerant liquid, which is at relatively low temperature, to keep the walls of the passage around the restriction 21 cool enough to condense some of the relatively inert propellant vapor in contact therewith, which otherwise would have uselessly increased the volume of vapor to be compressed. The refrigerant pressures given above are merely by way of example and if it is desired to vary the temperature within the cooler 1 the rate of vaporization in the vaporizer may be varied which will result in varying the pressure of the vapors so that the rate of heat absorption in the cooler will accordingly increase or diminish. As water freezes at 4.6 mm. it is desirable that the vapor pressure in the cooler be maintained in approximately that region in order to obtain the best refrigerating effect. A slight amount of propellant fluid may pass into the cooler 1 and due to its relatively great liquid density will flow into the lower coil from which it is conducted into the vaporizer through a pipe 27.

which is connected to the pipe 22 at its lower end. A trap 28 filled with propellant liquid prevents refrigerant from flowing to the boiler.

- 5 It may be desirable under some conditions to lower the freezing point of the refrigerant medium in order to prevent its freezing in the cooler and for this purpose a suitable chemical or chemicals, such as an alcohol, 10 preferably one which with the refrigerant will produce a constant boiling mixture at a given pressure e. g. 4 mm., may be added thereto.

From the foregoing it will be evident that 15 the essence of the present invention, in a broad aspect, is the relation between the characteristics of the propellant and refrigerant fluids employed.

In another broad aspect the invention involves the use of propellant and refrigerant 20 circuits (13—2—18—19—19'—21—11—4—22—33 and 20—21—11—4—5—24—25—26—1) having a part in common (21—11—4) characterized by means for automatically 25 turning the propellant and refrigerant liquids from any part of the system to the vaporizer and cooler respectively. In the illustrated embodiment, for example, if mercury finds its way into the refrigerant condenser 5 or cooler 30 1 or other part of the refrigerant circuit, due to tipping or upturning the system or to its being carried to the refrigerant circuit by the refrigerant stream or in any other way, it is automatically returned to the vaporizer 35 by the normal operation of the system. That is, mercury may flow from the refrigerant condenser to the cooler through pipe 25 and trap 26 and thence from the cooler to the vaporizer through pipe 27 and trap 28. Thus 40 none of the propellant can be rendered useless by lodgment in some part of the refrigerant circuit other than said common part; and obviously the refrigerant can not become permanently lodged in any part of the propellant circuit. While limited amounts of 45 propellant are intentionally trapped at 26 and 28, any excess tending to accumulate in these traps runs over, to the cooler from trap 26 and to the vaporizer from trap 28.

50 From the foregoing it will be evident that the preferred way of obtaining this unique result is to employ pressure balancing means such as the mercury columns in ducts 22 and 27 and traps 23 and 28, which serve the double 55 function of balancing the pressures and permitting the automatic return of stray propellant.

It will also be evident that the novel relationship of parts (both fluid and solid) makes 60 it possible to employ pressures, the maximum of which may be of the order of an atmosphere, a pressure which is free from danger of explosion.

I claim:

- 65 1. A refrigerating system of the type em-

ploying a refrigerant fluid and a propellant fluid, comprising a propellant vaporizer, a propellant condenser in which propellant vapor is condensed at a suitable temperature, a refrigerant condenser, in which refrigerant vapor is condensed at a lower temperature, a 70 cooler, a duct for conducting propellant vapor from the vaporizer to the propellant condenser, a duct for conducting refrigerant liquid from the refrigerant condenser to the cooler, means for maintaining a lower pressure in the cooler than in the refrigerant condenser, an aspirator in said first duct, and a duct leading from the cooler to said aspirator, so that the propellant vapor flowing 75 from the vaporizer to the propellant condenser impels refrigerant vapor from the cooler to the refrigerant condenser, the propellant liquid having a relatively high boiling point and the refrigerant liquid having a relatively low boiling point whereby a high temperature drop can be obtained between the vaporizer and condensing means without employing high pressure in the vaporizer.

2. A refrigerating system of the type employing a refrigerant fluid and a heavier propellant fluid, comprising a propellant vaporizer, a propellant condenser, a vapor duct leading from said vaporizer to said condenser, a duct leading from said condenser back to said vaporizer for returning the condensed propellant back to the vaporizer, a refrigerant condenser, a duct leading from the propellant condenser to the refrigerant condenser, a cooler, a liquid duct leading from the refrigerant condenser to the cooler, a liquid trap in said last duct for maintaining a lower pressure in the cooler than in the refrigerant condenser by virtue of the weight of the liquid in the trap, an aspirator in said first duct, and a vapor duct leading from the cooler to said aspirator, whereby the propellant vapor impels the refrigerant vapor from the cooler to the propellant condenser, the propellant vapor being then condensed for return to the vaporizer and the refrigerant vapor passing on to the refrigerant condenser where it is condensed and delivered to the cooler.

3. A refrigerating system of the type employing mercury as a propellant fluid and a lighter refrigerant fluid, comprising a mercury vaporizer, a propellant condenser in which propellant vapor is condensed at a suitable temperature, a refrigerant condenser in which refrigerant vapor is condensed at a lower temperature, a cooler, a duct for conducting mercury vapor from the vaporizer to the propellant condenser, a duct for conducting refrigerant fluid from the refrigerant condenser to the cooler, an aspirator in said first duct, and a duct leading from the cooler to said aspirator, whereby the mercury vapor flowing 115 from the vaporizer to the propellant 120 condenser is impelled by the refrigerant vapor to the refrigerant condenser, the refrigerant vapor being then condensed and delivered to the cooler.

condenser impels refrigerant vapor from the cooler to the refrigerant condenser.

4. A refrigerating system of the type employing water as the refrigerant fluid and mercury as the propellant fluid, comprising a mercury vaporizer, a propellant condenser in which propellant vapor is condensed at a suitable temperature, a refrigerant condenser in which refrigerant vapor is condensed at a lower temperature, a cooler, a duct for conducting mercury vapor from the vaporizer to the propellant condenser, a duct for conducting water from the refrigerant condenser to the cooler, means for maintaining a low pressure in the cooler, an aspirator in said first duct, and a duct leading from the cooler to the said aspirator, whereby mercury vapor flowing from the vaporizer to the propellant condenser impels water vapor from the cooler to the propellant condenser and thence to the refrigerant condenser.

5. A refrigerating system of the type employing different refrigerant and propellant fluids, comprising a propellant vaporizer, a propellant condenser, a vapor duct leading from said vaporizer to said condenser, a duct leading from said condenser back to said vaporizer for returning condensed propellant back to the vaporizer, a refrigerant condenser, a cooler, a duct leading from the refrigerant condenser to the cooler, an aspirator in said first duct, a vapor duct leading from the cooler to the aspirator, whereby the propellant vapor impels the refrigerant vapor from the cooler to the refrigerant condenser, the propellant vapor being first condensed in the propellant condenser and returned to the vaporizer, and means in said last duct leading from the refrigerant condenser to the cooler for maintaining a lower pressure in the cooler than in the refrigerant condenser.

6. In a refrigerating system having a cooler containing refrigerant liquid, the method which comprises exhausting the cooler by entraining vapor from the cooler in a stream of the vapor of a liquid having a boiling point different from that of the refrigerant liquid, and condensing the vapors in different locations respectively for separate recirculation.

7. In a refrigerating system having a duct for conducting refrigerant vapor from a cooler to a dissipator, the method which comprises propelling the vapor from the cooler to the dissipator by entraining vapor from the cooler in the vapor of a propellant having a higher boiling point than the refrigerant, condensing substantially all the propellant vapor before it reaches the dissipator, and automatically draining from the cooler propellant which strays thereto.

8. In a refrigerating system having a duct for conducting refrigerant vapor from a cooler to a dissipator, the method which com-

prises propelling the vapor from the cooler to the dissipator by entraining vapor from the cooler in a stream of the vapor of a liquid having a higher boiling point than the refrigerant and being substantially immiscible therewith, condensing the propellant vapor before it reaches the dissipator and shunting it from said duct, revaporizing the condensed propellant vapor and again using it for aspiration as aforesaid.

9. In the art of refrigeration by circulating a refrigerant fluid with a propellant fluid, the method which comprises passing a gaseous propellant of comparatively high molecular weight from a region of substantial pressure to a region of lower pressure so that the propellant stream acquires considerable kinetic energy, and entraining in said propellant stream the vapor of a refrigerant having a vapor pressure of the order of a few percent of an atmosphere, and a molecular weight less than one-quarter that of the propellant whereby the pressures in said first region need not be high.

10. In the art of refrigeration by circulating a refrigerant fluid with a propellant fluid, the method which comprises passing a gaseous propellant from a region of substantial pressure to a region of lower pressure so that the propellant stream acquires considerable kinetic energy, and entraining in said propellant stream the vapor of a refrigerant having a molecular weight less than one-eighth of that of the propellant, whereby the energy loss due to impact of the propellant molecules with the refrigerant molecules is comparatively low.

11. In the art of refrigeration by circulating a refrigerant fluid with a propellant fluid, the method which comprises passing a gaseous propellant of comparatively high molecular weight from a region of substantial temperature to a region of lower temperature, introducing into said propellant stream the vapor of a refrigerant having a vapor pressure of the order of a few percent of an atmosphere at 0° C. and a molecular weight less than one-eighth that of the propellant whereby the pressure in said first region need not be high.

12. A refrigerating system comprising a vaporizer containing a propellant liquid, a cooler containing refrigerant liquid, said propellant having a higher boiling point than said refrigerant and being immiscible therewith, an aspirator nozzle adapted to receive vaporized propellant from the vaporizer, means whereby refrigerant vapor may be aspirated by the propellant stream emitted from the nozzle, a duct adjoining the outlet of the aspirator which is adapted to receive the stream of mixed propellant and aspirated vapors, a portion, of said duct being provided with cooling means to effect condensation of propellant and a second condenser por-

- tion forming a continuation of said duct to effect condensation of refrigerant, means for balancing the vapor pressure in the vaporizer, and for returning condensed propellant thereto from the duct, and a duct for returning condensed refrigerant from the second condenser portion to the cooler.
13. A refrigerating system comprising a propellant vaporizer, a cooler, propellant and refrigerant liquids of different boiling points in said vaporizer and cooler, respectively, an aspirator nozzle adapted to receive propellant and to discharge the same into a passage connected with the cooler whereby vapor from the cooler may be aspirated by a stream of propellant vapor, said passage being continued to provide successive condenser sections adapted to effect condensation of the propellant and refrigerant respectively, ducts connected to substantially the lowest parts of each of the condenser sections, one of said ducts being connected to the vaporizer to return condensed propellant thereto and the other of said ducts being connected to the cooler to return condensed refrigerant thereto, and means associated with the first-named duct to balance the difference in pressure between the corresponding condenser section and the vaporizer and yet to permit passage of liquid refrigerant to the same.
14. A refrigerating system comprising a propellant vaporizer, a cooler, propellant and refrigerant liquids of different boiling points in said vaporizer and cooler, respectively, an aspirator nozzle adapted to receive propellant and to discharge the same into a passage connected with the cooler whereby vapor from the cooler may be aspirated by a stream of propellant vapor, said passage being continued to provide successive condenser portions to effect the substantially separate condensation of the propellant and refrigerant, drains connected to substantially the lowest parts of each of the condenser sections, one of said drains being connected to the vaporizer to return condensed propellant thereto and the other of said drains being connected to the cooler to return condensed refrigerant thereto, said drains being arranged to hold liquid columns to permit differences in vapor pressure between the respective condenser sections and the vaporizer and cooler and yet to permit passage of condensed vapor to the vaporizer and cooler respectively.
15. A refrigerating system comprising a vaporizer containing a comparatively heavy propellant liquid, a cooler containing a comparatively light liquid, said liquids having different boiling points, means whereby vaporized refrigerant may be drawn from the cooler and entrained in a stream of vaporized propellant, a duct to receive the stream of mixed vapors, said duct including successive condenser sections, one of said sections having a drain to return condensed refrigerant to the cooler, the other of said sections having a drain to return the condensed propellant to the vaporizer, said last-named drain being arranged to contain a column of the heavy propellant liquid to balance the vaporizer.
16. A refrigerating system comprising a vaporizer containing mercury, a cooler containing a refrigerant liquid substantially immiscible with mercury an aspirator nozzle adapted to receive vaporized mercury from the vaporizer, means whereby refrigerant vapor may be aspirated by the propellant stream emitted from the nozzle, a passage adjoining the outlet of the aspirator which is adapted to receive the stream of mixed mercury and refrigerant vapors, a continuation of said passage being provided with cooling means to effect condensation of mercury and a second condenser portion forming a continuation of said passage to effect condensation of the refrigerant, and means for returning liquid mercury from the first condenser portion to the vaporizer.
17. A refrigerating system of the type using different propellant and refrigerant liquids in propellant and refrigerant circuits having a part in common, comprising a cooler containing refrigerant liquid in the refrigerant circuit, means including a vaporizer in the propellant circuit for circulating propellant therearound with the propellant in vapor form when it enters said common part, means for causing the propellant vapor in said common part to circulate refrigerant vapor from the cooler, means in said circuits for condensing the propellant and refrigerant vapors for return to the vaporizer and cooler respectively, and means for automatically returning the propellant and refrigerant liquids from any part of the system to the vaporizer and cooler respectively.
18. A refrigerating system of the type using different propellant and refrigerant liquids, in propellant and refrigerant circuits having a part in common, comprising a cooler containing refrigerant liquid in the refrigerant circuit, means including a vaporizer in the propellant circuit, for circulating propellant therearound with propellant in vapor form when it enters said common part, means for causing the propellant vapor in said common part to circulate refrigerant vapor from the cooler, and means in said circuits for condensing and returning the propellant and refrigerant to the vaporizer and cooler respectively, including means for automatically returning to the vaporizer propellant liquid which strays to the cooler.
19. A refrigerating system of the type using different propellant and refrigerant liquids, comprising propellant and refrigerant circuits having a part in common, a cooler containing refrigerant liquid in the refrigerant circuit, means including a vaporizer in

the propellant circuit for circulating propellant therearound with the propellant in vapor form when it enters said common part, means for causing the propellant vapor in said common part to circulate refrigerant vapor from the cooler, means in said circuits for condensing and returning the propellant and refrigerant to the vaporizer and cooler respectively, and pressure balancing means associated with said circuits permitting the automatic return to the vaporizer of propellant which strays to any part of the refrigerant circuit, said last means maintaining different pressures in the vaporizer, condensing means and cooler respectively.

20. A refrigerating system of the type using different propellant and refrigerant liquids in propellant and refrigerant circuits having a part in common, comprising a cooler containing refrigerant liquid in the refrigerant circuit, means including a vaporizer in the propellant circuit for circulating propellant therearound with the propellant in vapor form when it enters said common part, means for causing the propellant vapor in said common part to circulate refrigerant vapor from the cooler, means in said circuits for condensing the propellant and refrigerant for return to the vaporizer and cooler respectively, and pressure balancing means associated with said circuits permitting the automatic return to the vaporizer of propellant which strays to the refrigerant circuit, said last means including a column of propellant liquid in a duct through which propellant flows from the cooler to the vaporizer.

21. A refrigerating system of the type using different propellant and refrigerant liquids, propellant and refrigerant circuits having a part in common, a cooler containing refrigerant liquid in the refrigerant circuit, means including a vaporizer in the propellant circuit for circulating propellant therearound with the propellant in vapor form when it enters said common part, means for causing the propellant vapor in said common part to circulate refrigerant vapor from the cooler, means in said circuits for condensing the propellant and refrigerant for return to the vaporizer and cooler respectively, and pressure balancing means in the system permitting the automatic return to the vaporizer of propellant which strays to the refrigerant circuit, said last means including a trap in the path of refrigerant liquid flowing from the condensing means to the cooler.

22. A refrigerating system of the type using propellant and refrigerant liquids which are immiscible, the former being heavier than the latter, in propellant and refrigerant circuits having a part in common, comprising a cooler containing refrigerant liquid in the refrigerant circuit, means including a vaporizer in the propellant circuit for circulating propellant therearound with the prop-

pellant in vapor form when it enters said common part, means for causing the propellant vapor in said common part, to circulate refrigerant vapor from the cooler, means in said circuits for condensing the propellant 70 and refrigerant for return to the vaporizer and cooler respectively, and pressure balancing means associated with said circuits permitting the automatic return to the vaporizer of propellant which strays to the refrigerant circuit, said last means including a trap containing propellant in a duct through which propellant flows from the cooler to the vaporizer.

23. A refrigerating system of the type 80 using propellant and refrigerant liquids which are immiscible, the former being heavier than the latter, comprising propellant and refrigerant circuits having a part in common, a cooler containing refrigerant liquid in the refrigerant circuit, means including a vaporizer in the propellant circuit for circulating propellant therearound with the propellant in vapor form when it enters said common part, means for causing the propellant vapor in said common part to circulate refrigerant vapor from the cooler, means in said circuits for condensing the propellant and refrigerant for return to the vaporizer and cooler respectively, and pressure balancing means in the system permitting the automatic return to the vaporizer of propellant which strays to the refrigerant circuit, said last means including a trap containing the heavier propellant in a duct leading from the condensing means to the cooler.

24. A refrigerating system of the type using different propellant and refrigerant liquids, comprising propellant and refrigerant circuit having a part in common, a cooler 105 in the refrigerant circuit containing refrigerant liquid having a vapor pressure of the order of a few per cent. of an atmosphere, means including a vaporizer in the propellant circuit for circulating propellant therearound with the propellant in vapor form when it enters said common part, means for causing the propellant vapor in said common part to circulate refrigerant vapor from the cooler, means in said circuits for condensing and returning the propellant and refrigerant to the vaporizer and cooler respectively, and pressure balancing means for maintaining different pressures in the vaporizer, condensing means and cooler respectively, while confining the highest of said pressures to the order of an atmosphere.

25. A refrigerating system comprising mercury and water as propellant and refrigerant liquids respectively, mercury and water 125 circuits having a part in common, a cooler containing water in the refrigerant circuit, means including a vaporizer in the mercury circuit for circulating mercury therearound with the mercury in vapor form when it en-

ters said common part, means for causing the propellant vapor in said common part to circulate water vapor from the cooler, and means associated with said circuits for separately condensing and returning the mercury and water vapors to the vaporizer and cooler respectively.

26. In a refrigerating system having a duct for conducting refrigerant vapor from a cooler to a dissipator, the method which comprises propelling the vapor of a refrigerant having a boiling point much lower than that of mercury from the cooler to the dissipator by entraining vapor from the cooler in a stream of mercury vapor and condensing the latter before it reaches the dissipator.

27. In a refrigerating system having a duct for conducting refrigerant vapor from a cooler to a dissipator, the method which comprises propelling water vapor from the cooler to the dissipator by entraining the water vapor from the cooler in a stream of mercury vapor and condensing the latter before it reaches the dissipator.

28. In a refrigerating system having refrigerant and propellant circuits with a part in common, the art of refrigeration which comprises employing a heavy propellant of high boiling point and a lighter relatively volatile refrigerant which is substantially immiscible with the propellant, vaporizing the propellant in one part of its circuit, entraining refrigerant vapor from a liquid body of refrigerant in a stream of the vaporized propellant, subjecting the resulting stream of mixed vapors to a cooling effect to condense the propellant, subsequently condensing the refrigerant, returning the condensed refrigerant to the cooler, directing the condensed propellant to the top of a liquid column, feeding propellant from the lower end of the same to the region of propellant vaporization, and thus continuously circulating the liquids while depending upon their different weights and their immiscibility to keep them substantially separated except in the common part of the circuits.

29. The art of refrigeration which comprises vaporizing a refrigerant in the region to be cooled by entraining it in a stream of propellant vapor having a higher weight and a higher condensation point than that of the refrigerant vapor, condensing the propellant out of the refrigerant and subsequently condensing the refrigerant in a separate region.

30. A refrigerating system comprising a cooler, a nozzle, a duct for directing refrigerant vapor from said cooler to said nozzle, means whereby propellant vapor may draw said refrigerant through said duct and become mixed with said refrigerant vapor, a condenser for one of said vapors, and a second condenser between the nozzle and the first condenser for the other of said vapors.

31. A refrigerating system comprising a cooler, an aspirator nozzle, a duct for conducting refrigerant vapor from said cooler to said nozzle, means whereby aspirated propellant vapor may draw said refrigerant through said duct and become mixed with said refrigerant vapor, and two condensers situated at different levels and connected with the outlet of said nozzle and said duct, the heavier of the two vapors collecting and condensing in the lower condenser and the lighter vapor separating from the heavier vapor and condensing in the upper condenser.

Signed by me at Boston, Massachusetts, this eleventh day of August, 1924.

EASTMAN A. WEAVER.
